UNITED STATES PATENT OFFICE.

RALPH A. DURLAND, OF NEWBURGH, NEW YORK.

DESIGN FOR A COMBINED RADIATOR CAP AND THERMOMETER.

Application filed April 12, 1923. Serial No. 5,793. Term of patent 3½ years.

To all whom it may concern:

Be it known that I, RALPH A. DURLAND, a citizen of the United States, residing at Newburgh, in the county of Orange and State of New York, have invented a new, original, and ornamental Design for a Combined Radiator Cap and Thermometer, of which the following is a specification, reference being had to the accompanying drawing, forming part thereof.

Figure 1 is an elevation of the combined radiator cap and thermometer, showing my design,

Figure 2 is a top plan thereof.

I claim:

The ornamental design for a combined radiator cap and thermometer, as shown.

RALPH A. DURLAND.
